United States Patent

[19]

Shulze

[11] Patent Number: Des. 424,192

[45] Date of Patent: ** May 2, 2000

[54] MEDICAL PRESSURE TRANSDUCER FOR
MEASURING BLOOD PRESSURE

[75] Inventor: **John E. Shulze**, Rancho Santa
Margarita, Calif.

[73] Assignee: **Sunscope International, Inc.**, Newport
Beach, Calif.

[**] Term: **14 Years**

[21] Appl. No.: **29/075,385**

[22] Filed: **Aug. 18, 1997**

[51] LOC (7) Cl. **24-02**

[52] U.S. Cl. **D24/107**

[58] Field of Search **D24/107, 108,
D24/129, 164, 169, 187; 600/488, 486,
561; 73/706, 708, 721, 715**

[57] CLAIM

The ornamental design for a medical pressure transducer for measuring blood pressure, as shown and described.

DESCRIPTION

FIG. 1 is a front perspective view of a medical pressure transducer for measuring blood pressure showing my new design;

FIG. 2 is a right side elevational view thereof;

FIG. 3 is a left side elevational view thereof;

FIG. 4 is a front elevational view thereof;

FIG. 5 is a rear elevational view thereof;

FIG. 6 is a top plan view thereof; and,

FIG. 7 is a bottom plan view thereof.
